UNITED STATES PATENT OFFICE.

CHARLES J. DIEGES, OF NEW YORK, N. Y.

DESIGN FOR A BADGE.

47,555.

Specification for Design. Patented July 13, 1915.

Application filed February 20, 1915. Serial No. 9,727. Term of patent 7 years.

To all whom it may concern:

Be it known that I, CHARLES J. DIEGES, a citizen of the United States, residing in the borough of Manhattan, city, county, and State of New York, have invented a new, original, and ornamental Design for a Badge, of which the following is a specification, reference being had to the accompanying drawing.

The figure is a front elevation upon an

enlarged scale, showing my new design for a badge.

I claim,
The ornamental design for a badge, as shown.

CHARLES J. DIEGES.

Witnesses:

D. W. GARDNER,
GEO. MEYER.
